US00D771246S

(12) **United States Design Patent** (10) Patent No.: **US D771,246 S**
 Raycheck et al. (45) Date of Patent: ** Nov. 8, 2016

(54) **FOLDED ABSORBENT ARTICLE**

(71) Applicant: **The Procter & Gamble Company**, Cincinnati, OH (US)
 (72) Inventors: **Jeromy Thomas Raycheck**, South Lebanon, OH (US); **Kathleen Marie Lawson**, West Chester, OH (US); **Abhishek Prakash Surushe**, Schwalbach am Taunus (DE); **Theodore Cory Fites**, Cincinnati, OH (US); **Andrew James Sauer**, Cincinnati, OH (US); **Sara Lyn Giovanni**, Cincinnati, OH (US)

(73) Assignee: **The Procter & Gamble Company**, Cincinnati, OH (US)

(**) Term: **14 Years**

(21) Appl. No.: **29/520,801**

(22) Filed: **Mar. 18, 2015**

(51) LOC (10) Cl. **02-01**

(52) U.S. Cl.

USPC **D24/126**
